[57] CLAIM

The ornamental design for a floppy disk cartridge, as shown and described.

DESCRIPTION

FIG. 1 is a front, top and left side perspective view of a floppy disk cartridge showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof;

FIG. 7 is a right side elevational view thereof; and

FIG. 8 is a cross-sectional view thereof taken about line 8—8 of FIG. 2.

Fig. 1

8. *Fig. 2**Fig. 3**Fig. 4**Fig. 5**Fig. 6**Fig. 7**Fig. 8*
